UNITED STATES PATENT OFFICE.

PETER JAY SCHELB, OF FORT WORTH, TEXAS.

DESIGN FOR A DISPLAY SIGN.

Application filed September 23, 1927. Serial No. 23,534. Term of patent 7 years.

To all whom it may concern:

Be it known that I, PETER JAY SCHELB, a citizen of the United States of America, residing at Fort Worth, in the county of Tarrant and State of Texas, have invented a new, original, and ornamental Design for Display Signs, of which the following is a specification, reference being had to the accompanying drawing, forming a part thereof.

The figure is a front elevational view of a display sign showing my new design.

I claim—

The ornamental design for a display sign as shown.

PETER JAY SCHELB,
